UNITED STATES PATENT OFFICE.

WALTER N. VANCE, OF CHICAGO HEIGHTS, ILLINOIS, ASSIGNOR TO DURAND STEEL LOCKER COMPANY, OF CHICAGO, ILLINOIS, A CORPORATION OF ILLINOIS.

ART OF FORMING TUBES.

1,344,105.

Specification of Letters Patent. Patented June 22, 1920.

Application filed June 12, 1915. Serial No. 33,874.

To all whom it may concern:

Be it known that I, WALTER N. VANCE, a citizen of the United States, residing in Chicago Heights, in the county of Cook and 5 State of Illinois, have invented a new and useful Improvement in the Art of Forming Tubes, of which the following is a specification.

This invention relates to the art of forming tubes and has more particular reference to the provision of tubes of polygonal or 10 partial polygonal cross section.

Prior to my invention considerable difficulty has been experienced in the provision 15 of tubes provided with slots, perforations and the like, which are made in the stock before the tube is formed. Tubes in accordance with the usual practice are drawn through rolls, which operation destroys the 20 accuracy of any apertures or slots that may have been formed in the stock from which the tube is formed. If the tubes are made over mandrels the operation becomes expensive and requires cumbersome machinery.

It is a principal object of this invention to provide for the economical manufacture of tubes having accurate perforations or slots 30 without danger of distorting such perforations or slots in the forming of the tube and without the provision of complicated and difficultly operated machinery.

Other objects and advantages of the invention will be apparent as it is better understood from the following description when considered in connection with the accompanying drawing illustrating a preferred embodiment thereof.

Figure 1 is a sectional view through dies 40 provided for the initial bending of the tube of the character shown on the drawing;

Fig. 2 shows the same after its first operation;

Fig. 3 after the next operation;

Figs. 4 and 5 are views of a second set of dies used in forming a tube in accordance with my invention;

Fig. 6 is a view of the mechanism for 50 performing the final stage in the forming of the tube; and

Fig. 7 is a view of the finished tube.

For the purpose of illustrating this invention I have shown on the drawing a tube 55 generally designated at 8 of rectangular

cross section having closed edges 9, although it will be manifest that other forms of tubes may be made in accordance with my invention without departing from its spirit and scope.

In accordance with my invention it is intended to form the full length tube through a succession of steps, each step acting throughout the length of the tube and with equal force on all parts of it. This eliminates any drawing or tendency to distort the metal forming the tube which would destroy the accuracy of any apertures or slots provided in the stock. The stock is subjected to pure bending forces without being placed under tension which would damage it. It will be noted as the invention is better understood that certain parts of the tube are not operated upon at all in its formation. The tube is first bent to provide the desired 75 corners, the edges which are to abut being maintained in spaced relation through the deflection of a side of the tube as indicated generally in Fig. 5. Thereafter this deflection is eliminated to bring the edges together where they may be welded or otherwise secured together or left in mere abutment as desired.

For the purpose of illustrating this invention I have shown on the drawings two sets 85 of dies 10, 11 and 12, 13. In the tube shown on the drawing it is desired to have contacting outwardly extending edges 9 and to this end these edges are formed in the dies 10, 11, although they are by no means necessary to the invention. Viewing Fig. 1 it will be noted that the male die 10 is provided with two deflecting points 14 and the female die 11 with correspondingly shaped pockets 15. A sheet 16 of suitable width is placed between these dies with its edge 17 extending beyond the center of the female die a distance equal to the desired width of an edge 9. At the center of the die a hardened edge 19 may be positioned if desired. When the die 10 descends the stock of the sheet is bent, as seen in Fig. 2, forming an edge part 9 and a half of one side wall 21 of the finished tube. The other edge is similarly treated, as seen in Fig. 3. This 105 may be accomplished by inserting from the other side of the die or by mere turning end for end. The stock of the tube is then in the form shown in Fig. 4 and in this position is placed between the dies 12 and 13. 110

These dies bend the stock into the form shown in Fig. 5 and to this end the die 13 has inclined side walls 22 and a bottom wall 23 which is higher at its center than at the sides. This bottom wall is defined by two surfaces 24 disposed at right angles with the surfaces 22. The die 12 is faced in accordance with the bottom, being higher at its center 25 than at its edges 26 so that when the die descends the two longitudinal corners 27 are formed. This completes the formation of the tube corners, the other two corners 28 having been formed in the dies 10, 11. In fact this operation completes the formation of the tube except for the elimination of the deflection 29. This deflection holds apart the edges 9 of the stock and permits the withdrawal of the die 12. Although in the present instance this die is materially larger than the spaced distance between the edges 9 the flexibility of the material will permit it to be removed. The partly formed tube is then placed upon a smooth flat or slightly concaved support 31 and a pressure member 32 inserted between the edges 9 and moved downwardly to remove the deflection, bringing the edges 9 in close contact with the pressure member 32. The deflection is completely removed and the edges prevented from closing by pressure of the pressure member. Upward movement of the pressure member produces a removal of the pressure member from the tube through engagement with stripping members 33 which cause the tube to slide off the edge of the pressure member and the edges 9 to snap together. Thereafter the edges may be welded or otherwise secured as may be desired. If desired the stock may be bent in the manner described to slightly space the outward offsets or edges 9 in order that a partition may be inserted between them when the tubing is used for metal shelving. The tubes or posts may be provided with perforations 34 adapted to receive fastening members for cross-shelves or for other purposes and these perforations may be made in the stock in the flat, the pure bending action to which it is later subjected having no tendency to draw the material and destroy the accuracy of the perforations.

It is thought that the invention and many of its attendant advantages will be understood from the foregoing description, and it will be apparent that various changes may be made in the form, construction and arrangement of the parts without departing from the spirit and scope of the invention

or sacrificing any of its material advantages, the form hereinbefore described being merely a preferred embodiment thereof.

I claim:

1. The process of making closed sheet metal tubes of rectangular cross-section, which consists in forming all the longitudinal edges and deflecting one of the side walls to maintain the edges in separated relation, and subsequently returning said deflected wall to flat condition by the insertion of a pressure member between said edges and withdrawing said pressure member in a reverse direction laterally outwardly through said edges.

2. The process of making closed sheet metal tubes of rectangular cross-section, which consists in forming all the longitudinal edges and deflecting one of the side walls to maintain the edges in separated relation, and subsequently returning said deflected wall to flat condition by the insertion of a pressure member between said edges and withdrawing said pressure member in a reverse direction laterally outwardly through said edges, the dimensions of the tube parts being made such that they are brought into contact with the sides of the pressure member and come substantially into contact when the pressure member has been withdrawn.

3. The process of making closed sheet metal tubes of rectangular cross-section, which consists in forming all the longitudinal edges and deflecting one of the side walls to maintain the edges in separated relation, and subsequently returning said deflected wall to flat condition by insertion of a blade pressure member between the edges and withdrawing said pressure member in a reverse direction laterally through said edges.

4. A closed sheet metal tube of rectangular cross-section and formed by forming all of the longitudinal edges and deflecting one of the side walls to maintain the edges in separated relation, and subsequently returning said deflected wall to flat condition by the insertion of a pressure member between said edges and withdrawing said pressure member in a reverse direction laterally outwardly through said edges.

Signed in the presence of two subscribing witnesses.

WALTER N. VANCE.
